Attorney:

UNITED STATES PATENT OFFICE.

ALBERT S. NEWTON, OF PROVIDENCE, RHODE ISLAND.

SANITARY DRINKING-FOUNTAIN.

1,236,101.

Specification of Letters Patent.

Patented Aug. 7, 1917.

Application filed November 27, 1916. Serial No. 133,532.

To all whom it may concern:

Be it known that I, ALBERT S. NEWTON, a citizen of the United States, residing at Providence, in the county of Providence and 5 State of Rhode Island, have invented certain new and useful Improvements in Sanitary Drinking-Fountains, of which the following is a specification.

My invention relates to bubblers or sanitary drinking fountains and has for its primary objects the shielding of the drinker's lips from the discharge orifice; the maintenance of a uniform height of the discharge stream; the prevention of radial discharge 15 to a distance from the nozzle when it is attempted to deflect the stream from the discharge orifice; and to positively direct the water along the finger and up to the wrist and clothing of any person who places his 20 finger upon the stream at its point of emission, and in such a manner as to discourage such mischievous interference. Further objects are to secure the above ends in a simple and inexpensive structure easily operable.

To the enumerated ends essentially my invention consists in such parts and combinations of parts as fall within the scope of the appended claim.

30 In the accompanying drawings which form a part of this specification

Figures 1 and 2 are side and plan elevations of my novel structure,

Fig. 3, a section on line 3—3 of Fig. 2, 35 and

Fig. 4, a section on line 4—4 of Fig. 1.

Like reference characters indicate like parts throughout the views.

My invention in the form thereof herein 40 shown comprises an attaching sleeve 6 provided with internal threads 7 adapted to engage the threads of the supply pipe. The upper portion of this sleeve constitutes an attaching post 8 provided with a threaded central opening 9 communicating with the 45 interior of the portion 6, but of less diameter. A nozzle 11 has an external threaded connection 12 in the threaded orifice 9 of the post, and projects slightly above the post.

50 The nozzle has an inclined bore 14 extending longitudinally thereof, eccentric to the nozzle at its bottom, but concentric thereto at its top. The water passing through the sleeve 6 and the inclined bore 14 is therefore discharged at an inclination,

The upper end of the post 8 is provided with an external thread 16 adapted to engage an internal thread 17 upon the lower end of a cap or housing 18, comprising a side wall 19, and a top wall 20, the latter being 60 provided with a central orifice 21 of greater diameter than the diameter of the bore 14 of the nozzle, and directly above the latter. The wall 19 is provided with a plurality, in the present instance 3, openings 23 arranged 65 equidistant from each other. Since the cap is somewhat cup shaped, the interior thereof near its top is inwardly and upwardly inclined as is 25 and the adjacent opening 21 is provided with a bevel 26. This beveled 70 formation is of importance in assisting the guidance of the stream when the latter is being intercepted by the finger of a person attempting to cover the opening 21, because it has a tendency to direct the flow of the water 75 up and over the top of the finger toward whatever direction the finger approaches to cover the opening, and thus insures the wetting of the upper portion of the hand, wrist or clothing. Near the upper portion of the 80 sleeve 6 are a plurality, in the present instance 3, radially disposed, upwardly directed, outwardly inclined arms 28 connected at their outer ends with a ring 29. The ring 85 forms a guard.

In operation, unless some obstacle is present, the stream issues from the supply pipe through the sleeve 6 and nozzle 11, and through the opening 21 in the cap in an inclined direction without interference, with 90 the cap itself, and at a reasonable and uniform height. The inclined character of the stream, and the inclination and bevel of the interior surface of the cap combine to efficiently effect the ends already suggested. 95

It will be observed that the openings 23 are located in each instance directly opposite the arms 28 so that the waste water issuing from said openings when the stream is intercepted is directed toward these radial 100 arms which act as shields against the excessive dispersion of the water from the fountain.

It will be further observed that one of the purposes of this invention is served by the 105 threaded character of the connection of the nozzle with the post, and the threaded character of the connection of the housing with the post, whereby these members may not only be readily assembled and re-assembled 110

with the remaining parts, but are capable of adjustment relatively to each other and relatively to the post and guard ring.

I claim:—

- 5 In a drinking fountain, the combination of a hollow post, of a nozzle seated in the post, a cap inclosing the nozzle detachably embracing the post with its lower margin, inclined guard arms upon the post extended
10 above the cap, a guard ring upon the ends

of the arms, said cap being provided with an opening in its top and with lateral openings in radial alinement with the arms.

In testimony whereof I have affixed my signature in presence of two witnesses.

ALBERT S. NEWTON.

Witnesses:

HORATIO E. BELLOW,
CHARLES S. JENCKES.
